UNITED STATES PATENT OFFICE.

RALPH D. NYE, OF COLUMBUS, OHIO.

FURNACE VALVE.

Application filed December 2, 1926. Serial No. 152,185.

The invention relates to an air reversing valve for open hearth and other furnaces of the regenerative type; and the object of the improvement is to provide an improved air reversing valve for controlling and reversing the flow of air through the furnace and regenerators; to provide a water-cooled valve seat for each of the air valves; to provide means for causing each valve to seat tightly when in the lowered position, wedging the lower edge of the valve tightly against the seat and tilting the upper portion of the valve into close relation with the seat; to provide integral ribs or projections upon the valve seats, forming supports for the springers or haunches of the masonry arch of the chimney flue; and to generally improve and simplify the construction and operation of reversing valves.

An embodiment of the invention is illustrated in the accompanying drawings, forming part hereof, in which

Figure 1 is a vertical sectional view through the improved air valve mechanism; Fig. 2, a sectional elevation taken substantially on the line 2—2, Fig. 1;

Fig. 3, a plan elevation taken substantially on the line 3—3, Fig. 1;

Fig. 4, a side elevation of the improved valve seat, and

Fig. 5, a vertical section through the same taken substantially on the line 5—5, Fig. 4.

Similar numerals refer to similar parts throughout the drawings.

The improved valve mechanism may be used in connection with any ordinary open hearth or other furnace built with the usual air tunnels 1 at each end, extending through regenerators in the usual manner and leading to the common chimney flue 2, opening

into the bottom of the chimney stack, by means of which an induced draft is created for moving air one way or another through the furnace.

These air tunnels open straightaway into the sides of the common chimney flue, and are also provided with the upwardly disposed ports 3 opening into the sides of the air box 4.

The gate valve 5, carried by the cables 6, which may be operated in any usual and well known manner, may be provided for closing the open, top side of the air box and for regulating the amount of air admitted thereto.

The improved valve seats 7 are prefer-

ably in the form of rectangular castings, mounted one upon each side of the chimney flue and air box. These valve seats are preferably inclined toward each other, at their upper ends, as clearly illustrated in Fig. 1 and spaced ribs or projections 8 and 9 may be formed upon the inner face of each valve seat to support the springers or haunches 10 of the several courses or tiers of the arch 11 of the common chimney flue.

An air port 12 is provided in the upper portion of each valve seat forming a communication between the passages 3 and the air box 4, and a flue opening 13 is provided in the lower portion of each valve seat providing a communication between the air tunnels 1 and the chimney flue 2.

The casting forming each valve seat is enlarged or thickened around the flue opening, as indicated at 14, and a continuous, unjointed pipe is imbedded therein and extends entirely around the flue opening as shown at 15, the ends thereof then extending upward, upon the inner side of the valve seat, and across the air port as indicated at 16, receiving the cooling influence from the air box, and terminating in the angular out-turned ends 17.

One end 17 is connected to the corresponding end of the pipe in the other valve seat, as by the coupling 18, the other outturned end of each pipe communicating with a pipe 19. One of the pipes 19 may be connected to a suitable source of supply of water or other cooling agent and the other pipe 19 leads to a suitable drain, whereby cooling water may be continuously circulated through both valve seats and around the flue openings therein.

The gate valves 20 may be in the form of rectangular castings, slidably mounted against the outer faces of the valve seats and preferably supported and operated by cables 21 secured to the ends of a rocking beam 22, mounted upon the rock shaft 23, which is journaled in bearings 24 upon the brackets 25, supported upon the upper ends of the valve seats. These gate valves have recesses cast therein to contain refractory lining or the like.

Pulleys 26 may be provided for guiding the cables 21, and to press the gate valves against the valve seats in the raised position. The shaft 23 may be rocked, as by the link 27 connecting the rocker arm 28 upon the shaft 23, with a crank arm 29, operated from

any suitable source of power, as through the reduction gearing 30, or may be operated by an air cylinder.

The lower edge of each gate valve is preferably beveled, substantially upon an angle of forty-five degrees, as shown at 31, and spaced from the lower end of each valve seat is located a bar 32 having its inner face beveled substantially at an angle of sixty degrees as shown at 33. These bars may be rigidly connected together in spaced position as by the tie bar 34.

When each gate valve 20 is moved to its lowered position, as shown at A in Fig. 1, the beveled edge 31 of the gate valve will be wedged against the beveled edge 33 of the bar 32, tightly wedging the lower end portion of the gate valve against the valve seat and tending to tilt the upper portion of the gate valve tightly against the valve seat, thus effectually closing the flue opening 13.

The mechanism is so arranged and adjusted that when one gate valve 20 is dropped downward, to close the corresponding flue opening 13, as indicated at A in Fig. 1, the other gate valve will be raised to close the corresponding air port 12, as indicated at B in the same figure.

This position of the valves gives a wide open communication from the air box 4, through the left hand port 12 and corresponding air passage 3 and into the left hand air tunnel 1, as indicated by arrows on the left side of Fig. 1; while a wide open direct communication from the other air tunnel 1 through the corresponding flue opening 13 and into the chimney flue 2 is provided, as indicated by the arrows on the right hand side of Fig. 1.

Thus the induced draft of the stack will circulate the air into the furnace through one of the tunnels 1, and from the furnace through the other tunnel 1, and it will be obvious that this circulation will be reversed by reversing the positions of the valves 20.

I claim:

1. A valve mechanism for furnaces including an upright water-cooled valve seat, a gate valve slidably mounted against said seat, a bar spaced from the lower end of the seat and having a beveled inner face, and the lower end of the gate valve being beveled at a less angle than the bar, whereby the upper portion of the valve is tilted against the seat when in lowered position.

2. In a reversing valve mechanism for regenerative furnaces and the like, two water-

cooled valve seats, a common chimney flue having a masonry arch, the two valve seats located in the sides of said flue and comprising castings provided with integral projections forming supports for the springers of said arch.

3. A valve mechanism for furnaces including two inclined valve seats located in the sides of a common chimney flue, gate valves slidably mounted against said seats, a bar spaced from the lower end of each seat and having a beveled inner face, and the lower end of the gate valves being beveled at a less angle than the bars, whereby when the valves are in lowered position the lower ends of the gate valves are wedged against the seats and the upper ends thereof are tilted against the seats.

4. In a reversing valve mechanism for regenerative furnaces and the like, a common chimney flue, two valve seats located in the sides of said flue and having flue openings therein, the flue having a masonry arch having its springers supported upon said valve seats and an air box above said flue, the valve seats extending above the flue and forming two of the sides of said air box, and having ports communicating with said air box.

5. In a reversing valve mechanism for regenerative furnaces and the like, a common chimney flue, two water-cooled valve seats located in the sides of the flue, an air box above said flue, air tunnels at each side of the flue, said valve seats having flue openings forming communication between said air tunnels and the flue, a gate valve slidably mounted upon each seat and having a refractory lined inner face, and adapted to form a wall of the flue when in lowered position, and a passage between the air box and each tunnel whereby each valve when in lowered position is cooled upon its outer face by air passing from the air box to the adjacent tunnel while the inner face of the valve is subjected to the cooling influence of the water-cooled valve seat.

6. In a reversing valve mechanism for regenerative furnaces and the like, a valve seat, a chimney flue having a masonry arch, the valve seat located in the side of said flue and comprising a casting provided with an integral projection forming a support for the adjacent springer of the arch.

In testimony that I claim the above, I have hereunto subscribed my name.

RALPH D. NYE.
